DORSETT A. DAVISON AND GEORGE E. DAVISON, OF RICHMOND, VIRGINIA, ASSIGNEES
TO THE DAVISON ENGINEERING CORPORATION, OF RICHMOND, VIRGINIA, A COR-
PORATION OF VIRGINIA

INTERNAL COMBUSTION ENGINE

Application filed June 10, 1929. Serial No. 389,805.

Our invention relates to internal combustion engines, and our general purpose is to provide improved means for conducting gases to and from the cylinder or cylinders of such engines.

More particularly, our invention relates to internal combustion engines of the type in which rotary valves are employed for conducting gases to and from the cylinders there-
of, and our more specific purpose is to pro-
vide various improvements in the manner of
mounting, sealing, lubricating, cooling and
driving such valves, whereby they are ren-
dered thoroughly practical and highly effi-
cient in use.

Our inventive ideas are capable of embodiment in different mechanical structures, cer-
tain of which are illustrated in the accom-
panying drawings. It is to be understood,
however, that the structures shown are in-
tended merely as disclosures of the essential
features and novel characteristics of our in-
vention in certain practical forms, and that
not only are the structures shown capable of
modification in various respects, but that our
ideas in general are capable of inclusion,
either singly or collectively, in other struc-
tural arrangements, within the spirit and
scope of our invention as defined in the ap-
pended claims.

In the drawings, wherein like characters
of reference denote corresponding parts in
related views:

Figure 1 is a cross section of an internal
combustion engine having our improvements
embodied therein according to one form of
our invention, said section being taken on the
line 1—1 of Fig. 2.

Figure 2 is a fragmentary section on the
line 2—2 of Fig. 1.

Figure 3 is a perspective view of the rotary
valve employed in the forms of our invention
illustrated in Figs. 1 and 7.

Figure 4 is a perspective view of the port
bushing employed in the forms of our inven-
tion illustrated in Figs. 1 and 7.

Figure 5 is a view similar to Fig. 1, illus-
trating an alternative form of our inven-
tion.

Figure 6 is a view similar to Figs. 1 and 5

illustrating another alternative form of our
invention; and

Figure 7 is a view similar to Figs. 1, 5 and
6 illustrating a further alternative embodi-
ment of our invention.

Referring to the drawings in detail, it will
be observed that the present engine in general
construction, is of conventional design, in-
cluding, in each embodiment thereof herein
illustrated, a cylinder 10, water jacketed as 60
indicated at 12, a cylinder head 14, and a pis-
ton 16.

In accordance with our improvements
shown in Figs. 1 to 4 of the drawings, the
cylinder 10 is counterbored at its outer end 65
as indicated at 18, and disposed within said
counterbore is a port bushing 20, provided
with circumferentially spaced intake and ex-
haust ports 22 and 24, respectively, which
are disposed in alignment with complementary 70
laterally extending intake and exhaust ports
26 and 28 formed in the cylinder 10.

Formed near the outer end of the cylinder
10 and opening into the counterbored portion
18 thereof is a pinion housing 30 within which
is disposed a spiral pinion 32 adapted to be
driven in any suitable manner from the crank
shaft of the engine.

Disposed within the port bushing 20 is a
hollow, cylindrical valve 34 having an outer 80
end portion 36 of reduced internal and exter-
nal diameter disposed outwardly of the port
bushing 20. Mounted on the exterior of this
reduced portion is a spiral gear 38 in mesh
with the pinion 32 whereby, during opera- 85
tion of the engine, the valve is rotated.

Provided in the valve 34 is a port 40 which
is adapted, by rotation of the valve, to aline
successively with the intake and exhaust ports
22 and 24 in the port bushing 20.

At the advance end of the port 40, as re-
gards the direction of rotation of the valve
34, the latter is longitudinally split by a
kerf 42 which extends from the inner end
of the valve a short-distance beyond the port
40 and at its other end joins one end of a
kerf 44 which extends from the kerf 42 cir-
cumferentially of the valve, in the direction
of rotation thereof, any suitable distance
partly therearound. The valve thus formed 100

consists of a rigid lead end portion in the vicinity of the port 40, and a trailing end portion which is laterally or radially flexible, this construction assuring tight seating of the valve at all times against the inner face of the port bushing 20 and providing for free and easy rotation of the valve. The cylinder head 14 extends through the valve 34 and a short distance into the cylinder 10, its inner end portion 46 snugly fitting the cylinder directly inwardly of the counterbored portion 18 thereof. At its outer end said cylinder head is inclusive of a portion 48 of reduced external diameter forming a bearing on which the reduced portion 36 of the valve 34 is journaled for rotation, the intermediate portion of said cylinder head being of less external diameter than its inner end portion 46 and of greater external 20 diameter than its outer end portion 48, whereby a space is provided between the cylinder head and the port bushing to snugly receive the valve 34.

By reason of the reduced portions 36 and 48 of the valve and the cylinder head, respectively, opposed shoulders are produced, and between these shoulders is interposed a wear ring or rings 50 adapted to take any inward end thrust such as may be imparted 30 to the valve by the pinion 32.

To hold the valve against outward movement a cap member 52 is bolted to the outer end of the cylinder, a cylinder head centering ring 54 is disposed between the cylinder head and the counterbored portion of the cylinder, and an outer thrust ring 56 is disposed between this centering ring and the outer end of the valve, these rings serving also to eliminate any possibility of the gear 40 38 moving outwardly from the valve.

Formed in the cylinder head 14 is a combustion chamber 58 which opens into the cylinder 10 and which is inclusive of laterally extending intake and exhaust ports 45 60 and 62, respectively disposed in alinement with the bushing ports 22 and 24. Outwardly of these ports the intermediate portion of said cylinder head has formed in the outer face thereof an annular groove in 50 which is disposed a series of sealing rings 64, preferably three in number, of the expansion type. One of these rings, the middle ring in this instance, spans the kerf 44 while the others, the two outer rings in this 55 instance, bear against the inner face of the valve to either side of said kerf, said rings being disposed in end to end abutting relation.

Also formed in the outer face of the intermediate portion of the cylinder head is another annular groove in which is disposed one or more sealing rings 66, this ring or rings sealing against the inner face of the valve between the port 40 and the inner end 60 of the valve. In addition, if desired but not

necessarily, a third annular groove may be formed in the outer face of the intermediate portion of the cylinder head to accommodate an expansion ring 68 for sealing engagement with the inner face of the valve between the rings 64 and the thrust ring 50.

The cylinder head 14 is of hollow construction to afford a cooling water containing space 70 which extends to the inner end of the cylinder head and which surrounds the combustion chamber 58, this space opening at the outer end of the cylinder head, through passages in the cap member 52, into a water containing cylinder cover 72 the interior of which is in communication with the water jacket 12. By this construction the valve 34 is subjected to the influence of cooling water both internally and externally, and in order to prevent stagnation and assure circulation of water through the cylinder head, the space 70 is divided by partition walls, indicated by dotted lines at 74 in Fig. 1 of the drawings, extending from the top of the combustion chamber to the top of the cylinder head, said partition walls 70 cooperating with partition walls 76 extending inwardly from the cover 72 whereby water in its circulation from one side to the other of the jacket 12 is caused to flow inwardly through one side of the space 70 and outwardly through the other side of said space.

A hole 78 to receive a spark plug is formed in the top wall of the combustion chamber 58 and opens into a tubular extension 80 of said wall, which extension projects outwardly through the cap member 52 and the cylinder cover 72 and has threaded thereon two nuts, one of which, 82, cooperates with said cap member to prevent inward movement of the cylinder head and to secure the latter properly positioned within the cylinder, and the other of which, 84, serves to hold the cylinder cover in assembly with the cylinder.

Referring now particularly to Figs. 1 and 4 of the drawings, it will be observed that the outer end portion of the port bushing 20 is counterbored as indicated at 86 and that said counterbore terminates in a shoulder located approximately in line with the kerf 44. Disposed within this counterbore is a series of sealing rings 88, alternate ones of which are of the expansion type and the remaining ones of which are either of the solid or of the contractile type. These rings are arranged in end to end abutting relation between the shoulder 86 and an abutment formed by the inner end of the gear 38.

Formed in the outer face of the port bushing 20 is a longitudinally extending channel 90 which opens through the outer end of the port bushing and at its inner end is disposed in alinement with a duct 92 in the cylinder 10 which is adapted for connection with a suitable source of suction, such as is provided

by an ordinary rectifier (not shown), connected with the intake manifold of the engine. As indicated in Fig. 2 of the drawings, the ducts 92 of multiple cylinder engines provided with the present improvements, open into a common manifold or header 94.

Formed through the wall of the port bushing 20 is a pair of small oil metering holes 96 which open at their outer ends into the channel 90 and which are spaced so as to align once during each complete revolution of the valve 34 with the portions of the kerf 42 disposed, respectively, inwardly and outwardly of the port 40.

Our engine, which is of the four-cycle type, in which the valve 40 is geared to make one complete revolution for each two complete strokes or reciprocations of the piston 16, operates as follows: As the piston moves inward on its intake stroke, explosive gases are drawn into the combustion chamber 58 through the port 40 which at this time aligns with the ports 22 and 60. Upon completion of the intake stroke of the piston, and as the latter begins its outward stroke, rotation of the valve 34 results in the port 40 moving from registration with the ports 22 and 60 and blanking of said ports by a solid portion of the valve, so that continued outward movement of the piston results in the gases being compressed within the combustion chamber 58. As the piston reaches its limit of outward movement on its compression stroke or cycle the gases are exploded in conventional manner, and the piston is driven inward on its power stroke, the port 40 during this time being blanked by the cylinder and cylinder head. Upon the piston approaching its limit of inward movement on its power stroke, and as it moves outward on its exhaust stroke, the port 40 moves into registration with the ports 24 and 62 to permit exhaust of the expended or burnt gases, the exhaust ports becoming blanked and the intake ports beginning to open by the time the piston again begins to move inward, whereupon the foregoing operations are repeated.

A pump (not shown) operated by the engine, continuously draws lubricant from the crank case of the engine and delivers it under suitable pressure into the pinion housing 30 through a header 98 and a duct 100, or in any other suitable manner. The outer end of the port bushing 20 is in open communication with the housing 30 and consequently there is a continuous circulation of lubricant from said housing, through the channel 90, the duct 92 and the header 94 back to the crank case. Therefore, by reason of the holes 96, lubricant will be delivered constantly to the outer face of the valve from the channel 90 and at the same time the sealing rings 88 will be lubricated directly from the housing 30. The holes 96 always are covered

by the valve 34 except when the kerf 42, during rotation of the sleeve, passes said holes. In this connection it will be observed that during operation of the engine the kerf 42 will pass the holes 96 at intake or suction cycle, at which instant the vacuum in the cylinder will be slightly higher than in the manifold or header 94, which is subject to intake manifold vacuum. Consequently, this instantaneous suction through the holes 96 in the direction of the combustion chamber will result, once during each revolution of the valve 34, in a charge of oil being drawn through the kerf 42 for the lubrication of the sealing rings 64, 66 and 68, and the adjacent faces of the valve and the cylinder head, the amount of the charge being metered or determined by the size of the holes 96.

When combustion occurs within the chamber 58 the ports 60 and 62 are blanked by portions of the valve which are exposed through said ports to the direct flame of combustion. Inasmuch, however, as these valve portions, immediately following the combustion period of the engine, rotate to positions behind portions of the cylinder head that are water cooled, heat is radiated quickly therefrom. Also, when combustion occurs, the high pressure gases of explosion will tend to escape outwardly through the ports 60 and 62 between the valve and the cylinder head. The sealing rings 64, 66 and 68, however, effectively resist this escape of pressure, and any pressure which may by any chance escape to the outer face of the valve will be effectively stopped by the sealing rings 88 due to their superimposed relation and to said series of rings being alternately of the expansion and of the solid or contractile type. Moreover, the rings 64 and 66, by their radial spring pressure against the flexible trailing end portion of the valve, assist in maintaining a tight seal of the valve against the inner face of the port bushing 20, and in conjunction with the sealing effect of the rings 88 enable the area of the combustion chamber to be minimized and permit of operation of the engine under relatively high compression.

With respect to the rings 88, it is manifest that any pressure to which the innermost ring is subjected, will be transmitted successively to the other of said rings, so that they will be forced tightly against one another and any possibility of escape of pressure between them will be effectively eliminated. Moreover, said rings will prevent lubricant from flowing from the housing 30 between the port bushing and the valve and flooding the combustion chamber.

In some instances it may be preferred to embody a valve mechanism of the type shown in Figs. 1 to 4 of the drawings in a structure differing primarily from the structure of Figs. 1 to 4 in the location of the spark plug

opening. For example, it may be desirable to have the spark plug opening disposed laterally with respect to the cylinder and open directly into the cylinder instead of into a combustion chamber in the cylinder head as shown in Fig. 1. Under such conditions the valve mechanism may be embodied in a structure such as is shown or as may be suggested by the illustration in Fig. 5 of the drawings, wherein the spark plug opening 78^a opens directly into the cylinder through one side of the wall thereof inwardly of the valve mechanism, designated generally at B, the said valve mechanism to all intents and purposes being substantially the same as the valve mechanism previously described.

For economy in manufacture and other reasons it may be preferred to have the port bushing fit into a portion of the cylinder of the same diameter as the portion thereof which is traversed by the piston. Fig. 6 illustrates how this may readily be accomplished by providing a lateral flange 102 at the outer end of the port bushing for engagement with a shoulder formed by a counter-bored portion of the cylinder of minimum depth, the cooperation of said flange with said shoulder limiting inward movement of the port bushing. Another slight modification illustrated in this figure of the drawings involves forming an inwardly directed flange 104 at the inner end of the port bushing to limit inward movement of the valve and to enable the inner end portion of the cylinder head to be formed of uniform external diameter, disconsidering, of course, the sealing ring grooves therein.

In each of the preceding figures of the drawings the structure illustrated contemplates that cooling water for that portion of the cylinder head disposed within the valve shall both enter and leave the cylinder head at the outer end thereof. Fig. 7 illustrates a construction wherein the water containing space of the cylinder head is in communication with the water jacket of the cylinder at the inner end of the cylinder head through a lateral opening or openings 106. This affords very free and open communication between the cylinder water jacket and the cylinder head and thereby materially assists in maintaining the valve cool during operation of the engine. Fig. 7 also illustrates that the entire valve mechanism may be embodied in a head removable as an entirety from the cylinder. Obviously, if desired, this removable head feature may be used in any of the embodiments of the invention previously described.

Our mechanism is simple in construction, relatively cheap and easy to produce and assemble, or disassemble, is readily accessible for adjustment or repair, is efficiently lubricated, relatively light and highly reliable and efficient in operation.

From the foregoing description considered in connection with the accompanying drawings, it is believed that the construction, operation and advantages of our improved engine will be fully understood. The parts are of such construction and so relatively arranged as to be capable of rapid assembly and disassembly, the working parts all are well sealed and cooled, and the lubricating system is quite simple in design, yet is highly efficient in operation.

We claim:

1. In an internal combustion engine, a cylinder, a cylinder head extending into said cylinder and having an inner end portion closely fitting said cylinder, an outer end portion of reduced external diameter and an intermediate portion of greater diameter than its outer end portion and of less diameter than its inner end portion, a rotary valve surrounding the intermediate portion of said cylinder head and including a bearing portion surrounding the reduced outer end portion of said cylinder head; and means for driving said valve.

2. In an internal combustion engine, a cylinder, a cylinder head extending into said cylinder and having an inner end portion closely fitting said cylinder, an outer end portion of reduced external diameter and an intermediate portion of greater diameter than its outer end portion and of less diameter than its inner end portion, a rotary valve surrounding the intermediate portion of said cylinder head and including a bearing portion surrounding the reduced outer end portion of said cylinder head, end thrust receiving means between the bearing portion of said valve and the intermediate portion of said cylinder head, and means for driving said valve.

3. In an internal combustion engine, a cylinder, a port bushing therein, a rotary valve seating against the inner face of said port bushing, an abutment outwardly of said port bushing, and valve sealing means between said abutment and an outer end portion of said port bushing.

4. In an internal combustion engine, a cylinder, a port bushing therein, a rotary valve seating against the inner face of said port bushing, an abutment outwardly of said port bushing, and valve sealing means between said abutment and an outer end portion of said port bushing, said sealing means comprising a series of sealing rings disposed in end to end abutting relation.

5. In an internal combustion engine, a cylinder, a port bushing therein, a rotary valve seating against the inner face of said port bushing, said port bushing including a counterbored outer end portion, an abutment, and valve sealing means disposed in the counterbore of said port bushing between said abut-

ment and the shoulder in the port bushing formed by the counterbore thereof.

6. In an internal combustion engine, a cylinder, a port bushing therein, a rotary valve seating against the inner face of said port bushing, said port bushing including a counterbored outer end portion, an abutment on said valve, and valve sealing means disposed in the counterbore of said port bushing between said abutment and the shoulder in the port bushing formed by the counterbore thereof.

7. In an internal combustion engine, a cylinder, a port bushing therein, a rotary valve seating against the inner face of said port bushing, said port bushing including a counterbored outer end portion, a gear surrounding said valve, means operating through said gear to drive said valve, and valve sealing means disposed in the counterbore of said port bushing between said gear and the shoulder in the port bushing formed by the counterbore thereof.

8. In an internal combustion engine, a cylinder, a rotary valve therein, driving means for said valve at the outer end thereof, a housing enclosing said driving means adapted to have a lubricant continuously supplied thereto during operation of the engine, a port bushing surrounding said valve, and means for lubricating said valve through said port bushing by lubricant taken from said housing.

9. In an internal combustion engine, a cylinder, a port bushing therein, a rotary valve within said port bushing, means providing a lubricant passage between said cylinder and said port bushing, a lubricant chamber located outwardly of said port bushing and in direct lubricant discharging communication with said passage, and means for supplying lubricant from said passage to said valve.

10. In an internal combustion engine, a cylinder, a port bushing therein, a rotary valve seating against the inner face of said port bushing, an outwardly directed abutment on said valve overlying an outer end portion of said port bushing in spaced relation thereto, and valve sealing means between said abutment and the outer end portion of said port bushing.

11. In an internal combustion engine, a cylinder, a port bushing therein, a rotary valve within said port bushing, a lubricant chamber located outwardly of said port bushing, said port bushing having a channel in the outer face thereof in communication at one end with said chamber and at its other end with a source of suction, and said port bushing further having lubricant metering holes formed therethrough leading from said channel to said valve.

12. In an internal combustion engine, a cylinder, a cylinder head extending into the

outer end of said cylinder and having an outer end portion of reduced diameter thereby providing an outwardly facing shoulder, and a rotary valve having a bearing portion surrounding said cylinder head, said bearing portion being of reduced internal diameter relative to the valve thereby to provide an inwardly facing shoulder for cooperation with the outwardly facing shoulder of the cylinder head to take end thrust of the valve.

13. In an internal combustion engine, a cylinder, a cylinder head extending into the outer end of said cylinder and having an outer end portion of reduced diameter thereby providing an outwardly facing shoulder, a rotary valve having a bearing portion surrounding said cylinder head, said bearing portion being of reduced internal diameter relative to the valve thereby to provide an inwardly facing shoulder for cooperation with the outwardly facing shoulder of the cylinder head to take end thrust of the valve, and end thrust receiving means disposed between said shoulders.

14. In an internal combustion engine, a cylinder, a cylinder head extending into the outer end of said cylinder and having an outer end portion of reduced diameter thereby providing an outwardly facing shoulder, a rotary valve having a bearing portion surrounding said cylinder head, said bearing portion being of reduced internal diameter relative to the valve thereby to provide an inwardly facing shoulder for cooperation with the outwardly facing shoulder of the cylinder head to take end thrust of the valve, means surrounding said cylinder head holding the same concentric with respect to the cylinder and within the outer end thereof, and end thrust receiving means interposed between said last named means and the outer end of the bearing portion of said valve.

15. In an internal combustion engine, a cylinder, a cylinder head extending into the outer end of said cylinder and having an outer end portion of reduced diameter thereby providing an outwardly facing shoulder, a rotary valve having a bearing portion surrounding said cylinder head, said bearing portion being of reduced internal diameter relative to the valve thereby to provide an inwardly facing shoulder for cooperation with the outwardly facing shoulder of the cylinder head to take end thrust of the valve, and means surrounding said cylinder head holding the same concentric with respect to the cylinder within the outer end thereof and cooperating with the outer end of the bearing portion of the valve to take end thrust of the valve in an outward direction.

In testimony whereof we hereunto affix our signatures.

DORSETT A. DAVISON.
GEORGE E. DAVISON.
